[57] ABSTRACT

A method is provided for reducing the air-blowing time required to activate a substantially pure alpha-olefin for reaction with anhydrous hydrogen bromide to produce a primary alkyl bromide. The method involves admixing at least four weight percent of a previously activated alpha-olefin with the substantially pure alpha-olefin prior to air-blowing.

HYDROBROMINATION OF ALPHA-OLEFINS

This invention relates to an improved method for activating an alpha-olefin for reaction with anhydrous hydrogen bromide to produce a primary alkyl bromide.

The addition of HBr to alpha-olefins to produce primary and secondary bromides is known. It is also known that primary alkyl bromides can be made by the addition of HBr to alpha-olefins in the simultaneous presence of free radical promoters, such as ultraviolet light (U.S. Pat. No. 2,307,522); extraneously added peroxides, such as organic peroxides (U.S. Pat. No. 2,058,466 and British Pat. No. 843,234); or air (U.S. Pat. No. 3,108,141). Other prior art appears to be contradictory (U.S. Pat. No. 3,336,403) in teaching the use of peroxides is undesirable due to polymerization problems, and further that the use of oxygen or air simultaneously with HBr is slow. Indeed, it has been found that in some instances the hydrobromination of alpha-olefins proceeded rapidly when air and HBr were simultaneously added while in other instances, the reaction was inexplicably slow. It was found, however, that for a substantially pure olefin, that is, an olefin which contains no detectable amount of oxygen containing materials of any type, the reaction with HBr in the simultaneous presence of air was uniformly slow, thus substantiating the general teachings in U.S. Pat. No. 3,336,403. The simultaneous addition of air and HBr must occur at a temperature less than about 50° C., even in the presence of a free radical promoter, if substantial amounts of secondary alkyl bromides are to be avoided. Thus, it was not possible to increase the temperature of the hydrobromination reaction in the simultaneous presence of air in order to speed up the slow reaction since, in so doing, substantial amounts of undesirable secondary bromides would result. It is for this reason that the prior art teaches the use of low temperature olefin activation such as the use of ultraviolet light, the addition of extraneous organic peroxides, such as benzoyl peroxide, or the prior formation of ozonides. All of these methods suffer from the difficulty that they are expensive and not easily controlled.

As described in copending Ser. No. 856,374 entitled "Activation of Olefins for Hydrobromination by Air-Blowing" and filed on the same date as this application in the names of Russell G. Hay, Clarence R. Murphy and William R. Walsh and assigned to the same assignee as this application, the above problems were obviated by pre-air-blowing the olefin at a temperature from 60° to 200° C. for a time sufficient to result in activation of the olefin and thereafter reacting the alpha-olefin with anhydrous HBr in the absence of an extraneously added catalyst at a temperature less than 50° C. to produce the desired primary alkyl bromide.

It is necessary to activate the olefin by air-blowing in the liquid phase. This creates problems, especially for the lower carbon number olefins, such as the butenes and pentenes, as the air-blowing temperature increases since higher pressure equipment is required to maintain the olefins in the liquid phase. The higher air-blowing temperatures are desired, however, since the time required to activate the olefins is inversely proportional to the temperature and the shorter contact times are obviously advantageous.

Methods were therefore sought to decrease the time required for air-blowing the olefins, especially at the

lower temperatures, so as to avoid the necessity for higher pressure equipment to maintain the olefins in the liquid phase. A method has now been discovered which involves recycling a small amount (about 5 percent) of activated olefins which in some manner serves to reduce the time required for activation of the remaining 95 weight percent inactive olefins by about two-thirds.

In accordance with the invention, the time required to air-blow and activate an alpha-olefin for hydrobromination is reduced by a process which comprises adding at least 4 weight percent of a previously activated alpha-olefin to the substantially pure alpha-olefin charge stock to the air-blowing zone.

The attached FIG. 1 is a simplified flow diagram of the process of this invention.

to FIG. 1, a substantially pure alpha-olefin enters reactor 10 through line 12 where it is contacted under suitable conditions with a gas containing free molecular oxygen which enters reactor 10 through line 14 to activate the olefin. The activated olefin is removed from reactor 10 through line 16 and is sent to hydrobromination reactor 20. A portion of the activated olefin in line 15 16 is removed through line 18 and is recycled and enters line 12 together with the substantially pure olefin into reactor 10. The amount of activated olefin recycled through line 18 amounts to at least about 4 weight percent of the total charge entering reactor 10. The anhydrous HBr is added to reactor 20 through line 22 and the hydrobrominated product is removed from reactor 20 through line 24 and is sent to a recovery scheme, not shown, for the recovery of the primary alkyl bromide.

The alpha-olefin charge stock can be any substantially pure alpha-olefin having from four to 30 carbon atoms per molecule and is preferably an alpha-olefin having from four to 10 carbon atoms per molecule. The alpha-olefin can suitably have the formula:

where R can be any hydrocarbon radical, preferably an alkyl radical having from one to 28 carbon atoms, and R' can be hydrogen or a saturated hydrocarbon radical having from one to 27 carbon atoms and wherein the sum of the carbon atoms in R and R' is from two to 28. Examples of suitable alpha-olefins include, but are not limited to:

butene-1;	pentene-1;
isobutylene;	hexene-1;
3-methylbutene-1;	4-ethylhexene-1;
octene-1;	dodecene-1;
decene-1;	octadecene-1;
tetradecene-1;	2-methyl-1-nonadecene;
eicosene-1;	tetracosene-1;
2-octyl-1-dodecene;	and mixtures thereof.

While any of the above alpha-olefins can be used in the process of this invention to insure the production of primary alkyl bromides without the need of an extraneously added free radical catalyst, the process of this invention is particularly applicable to the hydrobromination of substantially pure alpha-olefins. By "substantially pure alpha-olefins" is meant those alpha-olefins which are prepared by the telomerization of a low molecular weight olefin having from two to six carbon

atoms per molecule, such as ethylene, under telomerization conditions in the presence of a catalyst such as a Group IIIA metal alkyl such as defined below, for example, aluminum triethyl. Very pure olefins must be used in the telomerization process since the Group IIIA metal alkyls act as scavengers for any oxygen containing materials which might be present and reduce the efficiency of the telomerization reaction. Thus, the telomerization products which are obtained are substantially unreactive in the hydrobromination reaction as defined above. For example, the alpha-olefins freshly produced by the telomerization process result in a yield of less than 50 mole percent, usually less than 10 mole percent, primary alkyl bromide when reacted with anhydrous hydrogen bromide in the absence of an extraneously added catalyst at -10° to 0° C. in a time of about 2 hours. Yet another way to obtain the substantially pure alpha-olefins would be, of course, to distill the alpha-olefins in the contact presence of a Group IIIA metal alkyl having at least one metal to carbon bond. By a "Group IIIA metal" is meant boron, aluminum, gallium, indium and tellurium. By a "metal alkyl" is meant a metal alkyl wherein there is at least one metal to carbon bond, the carbon being a portion of an alkyl group. The metal alkyls can suitably have the formula:

where Me is any of the Group IIIA metals defined above and wherein at least one and preferably all of R_2 , R_3 and R_4 are alkyl radicals having between one and 10 carbon atoms and wherein any one or two of R_2 , R_3 and R_4 can be selected from the group consisting of hydrogen and halogen radicals. Usually the metal alkyl is an aluminum or boron trialkyl such as triisobutylaluminum or triisobutylboron.

As noted, the substantially pure alpha-olefin prepared as above was found to be substantially inactive for the addition of HBr in the absence of an extraneously added free radical promoter. The simultaneous addition of oxygen in the form of air with the HBr to the alpha-olefins proved to be a very slow reaction requiring more than 6 hours at 28° C. to produce any appreciable amount of product.

It was found that the olefins could be simply and effectively activated by pretreatment before the HBr addition, the pretreatment consisting of contacting the alpha-olefin charge stock or the gas containing free molecular oxygen at a temperature from 60° to 200° C. for a time sufficient to activate the alpha-olefins. By an "activated olefin" is meant one which results in a yield of at least 85 mole percent primary alkyl bromide when reacted with anhydrous hydrogen bromide in the absence of an extraneously added catalyst at -10° to 0° C. in a reaction time of less than 15 minutes. Attempts were made to determine the peroxide number of the activated olefins and correlate activity with peroxide number, but such attempts failed since the peroxide numbers were inconsistent and active olefins had a peroxide number level so low that it was beyond the scope of the method. Temperatures below 60° C. were

considered undesirable as the time required to activate the olefins was unreasonably extended. On the other hand, temperatures above 200° C. gave undesirably short air oxidation times. It was also found that if the time at any given temperature is too long, then for some unknown reason the alpha-olefin is deactivated for the hydrobromination reaction either with or without the addition of an extraneously added free radical promoter. The time and temperature must therefore be carefully correlated to result in an olefin which is active for the hydrobromination reaction without the need for an extraneously added free radical promoter. Minimum times as short as 1 minute or less are effective at the higher air-blowing temperatures, whereas minimum times on the order of 6 hours are required at the lower air-blowing temperatures of about 60° C.

The subject invention relates to air-blowing a substantially pure alpha-olefin as defined above containing at least about 4 weight percent of a previously activated olefin. The purpose of air-blowing in the presence of a small amount of previously activated olefin is to decrease the time required for the air-blowing operation. One of the advantages of the subject invention is that a lower air-blowing temperature can be employed to achieve activation in the same time which would be required at a higher temperature. It is thus possible to employ a wider range of air activation temperatures than was previously believed economically feasible. Using the methods of this invention, a suitable range of air-blowing temperatures can be from 50° to 200° C., with the preferred activation temperatures being from 60° to 150° C.

FIG. 2 attached is a plot on a semi-log paper of the time required vs. temperature to obtain an olefin in the Operative Region, which is the region where an olefin would be active for the hydrobromination reaction without the need for an extraneously added free radical catalyst. The times shown on FIG. 2, however, are those required without the use of the present invention. Thus, referring to FIG. 2, at 70° C. a minimum of 6 hours would be required to activate the alpha-olefin whereas at 170° C. about 1 minute is required. By operating the air activation step in accordance with the procedure of this invention, namely by air-blowing in the presence of at least about 4 weight percent of previously activated olefin, the total time required to activate the olefin would be reduced. For example, the activation of octene-1 by air-blowing at 70° C. would require, referring to FIG. 2, about 6 hours of air-blowing time whereas the octene-1 has been found to be activated in a time of only 2 hours at 70° C. by air-blowing a mixture of 95 percent substantially pure octene-1 and 5 weight percent previously activated octene-1. Similarly, care must be taken when using the procedure of the present invention not to conduct the air-blowing operation for a time such that the olefin becomes inactive for the subsequent hydrobromination reaction. Hence, the minimum activation time is reduced by about two-thirds when air oxidation occurs in the presence of about 5 weight percent active olefin, and the maximum time of air-blowing before reaching an inactive state would correspondingly be reduced by about two-thirds.

The minimum amount of activated olefin to recycle is critical and must be at least about 4 weight percent of the total charge entering the air-blowing reactor. The recycling of active olefins in amounts less than about 4 weight percent is ineffective in reducing the time required for activation in the air-blowing step. Larger amounts of activated olefins can be recycled if desired, but no further beneficial effects are received. Thus, quite unexpectedly, the use of greater amounts than about 4 weight percent of activated olefins does not aid in reducing the air-blowing time still further. As a result, whether 5 or 25 weight percent of the charge stock to the air-blowing reactor is composed of previously activated olefins, the time required for air-blowing is about the same and is considerably reduced over the case where only a substantially pure olefin is air-blown. Thus, the amount of recycled activated olefin which can be utilized in the process of this invention can vary from about 4 weight percent to 50 weight percent of the charge stock to the air-blowing step and even greater amounts of recycled olefins can be employed if desired. For economic reasons it is obviously preferable to employ the minimum amount of recycled activated olefins, and for this reason the preferred amount of recycled olefin is from 4 to 10 weight percent.

Activated olefins having a carbon number different than the substantially pure olefin can also suitably be added in the same amounts to decrease the air-blowing time, but these olefins are not preferred due to complications in the recovery procedure.

The activation of the substantially pure alpha-olefins occurs quite simply by passage of a gas containing free molecular oxygen through the liquid alpha-olefin at the desired activation temperature. The terms "air-blown" or "air-blowing" in this application refer to blowing with a gas containing free molecular oxygen which may be, but is not necessarily, air. Means should be provided for insuring intimate contacting between the gas containing free molecular oxygen and liquid olefins to be activated. For example, the gas containing free molecular oxygen can be added to the liquid olefin through a sparger which breaks up the gas into very small bubbles. While additional stirring is not required, it can be employed if desired. The gas containing free molecular oxygen can suitably be air, pure oxygen or molecular oxygen diluted with an inert gas such as nitrogen. The gas suitably contains from 15 to 100 mole percent free molecular oxygen and preferably from 15 to 40 mole percent free molecular oxygen. Amounts of oxygen in the activating gas less than about 5 mole percent would merely prolong the contact times necessary for activation as shown on FIG. 2. The preferred activating gas is, of course, air.

The activated olefin can then be charged to a hydrobromination reactor where it is contacted with anhydrous hydrogen bromide gas. The presence of moisture in the system in small quantities of about 1 percent or less is not harmful to the reaction, but moisture should be avoided as it may be harmful to the reaction equipment. The hydrogen bromide can be obtained from any suitable source, and how it is prepared or from whence it comes is not critical to the process of the subject invention.

The gaseous hydrogen bromide adds to the activated alpha-olefins in an anti-Markownikoff manner. Markownikoff stated in 1870 that if an unsymmetrical olefin is treated with hydrogen halide the addition will occur at the carbon-carbon double bond and that the hydrogen will attach itself to the carbon atom bearing the greater number of hydrogen atoms and that the halide would attach itself to the carbon atom bearing the least number of hydrogen atoms. Thus, the normal or Markownikoff addition would produce a secondary alkyl bromide whereas the anti-Markownikoff addition produces the more desirable abnormal or anti-Markownikoff primary alkyl bromide.

The hydrogen bromide addition reaction occurs rapidly in any reactor providing for good mass transfer between the gaseous hydrogen bromide phase and the liquid alpha-olefin phase. For example, suitable mass transfer conditions for the addition of the hydrogen bromide to the olefin are obtained by bubbling the hydrogen bromide gas through the liquid activated olefin using, for example, a porous plate gas distributor to insure small gas bubbles resulting in a large interphase area. It is also preferred, of course, to provide vigorous agitation of the liquid phase to aid in the mass transfer and also to insure the maintenance of the desirable low reaction temperatures to be defined below. Under the excellent mass transfer conditions, the reaction is over in a matter of minutes even employing the low reaction temperatures to be defined below.

A suitable range of reaction temperatures is from -30° to 50° C., with the preferred reaction temperatures between -10° and 30° C. The use of increased reaction temperatures is undesirable as the higher temperatures promote the normal or Markownikoff addition with the consequent formation of the less desirable, less stable secondary alkyl bromides. When the reaction is operated in the defined temperature range, rapid completion of the hydrogen bromide addition occurs with the suppression of the formation of secondary alkyl bromides. Thus, suitable reaction times are between 1 and 240 minutes, and in the preferred temperature range the reaction times are usually between 3 and 120 minutes.

The reaction pressure can suitably be between atmospheric and 100 psig or more. An increase in reaction pressure tends to increase the reaction rate. However, since the reaction rate is already quite fast at atmospheric pressure, the use of increased reaction pressures, while technically feasible, is not preferred for obvious economic reasons.

The hydrobromination reaction product which is composed predominantly of primary alkyl bromides and small amounts of secondary alkyl bromides is usually purged of excess hydrogen bromide in any suitable manner. For example, air, nitrogen or helium can be passed or bubbled through the reaction product until it is free of hydrogen bromide. The resulting hydrogen bromide free alkyl bromide reaction product can then, optionally, be neutralized using any suitable basic solution. For example, a 5 percent aqueous solution of sodium bicarbonate is satisfactory and produces an upper organic phase and a lower aqueous phase. For some applications, for example, esterification reactions, neutralization is not required nor desired. The upper organic phase containing the alkyl bromides can

then be separated and the alkyl bromide recovered in any suitable manner.

The crude alkyl bromide reaction product can also be recovered by purging with a non-reactive gas as described above and thereafter dissolving the alkyl bromide in about 1 to about 10 times its volume of a non-reactive solvent for the alkyl bromide, such as chloroform or petroleum ether. The solution of the alkyl bromide in the solvent is then neutralized as before with a weakly basic solution. Alternatively, the unneutralized solution of the alkyl bromide in the non-reactive solvent can be washed with water until neutral, and this procedure is preferred in the case of the more labile alkyl bromides. Whichever method is chosen to neutralize, the neutralized solution is then dried in any conventional manner, such as by drying over magnesium sulfate. The solvent can then be removed by evaporation or distillation under reduced pressure. The pure alkyl bromide reaction product can then be distilled from the dried solvent-free organic phase. The invention will be further described with reference to the following experimental work.

Octene-1, which was prepared by the telomerization of ethylene, was distilled from tri-n-butylaluminum in a nitrogen atmosphere to produce a substantially pure octene-1. The peroxide number of the distilled octene-1 was less than 0.1, the limit of ASTM Test 1832.

A series of runs was made wherein the distilled octene-1 was air-blown at varying temperatures and for varying times with and without the addition of 5 weight percent of a previously air-blown and activated octene-1. The results of this series of runs are shown in Table I below.

TABLE I

Hydrobromination of Octene-1 at -10°C. to 0°C.

Ex. No.	Air-Blowing Conditions		Hydrobromination Conditions		Mole % Primary Alkyl Bromide	Charge Stock
	Time Hrs.	Temp. °C.	Time Min.			
1	2	70	103		24	100% Substantially Pure Octene-1
2	6	70	6		95	100% Substantially Pure Octene-1
3	2	70	3		93	95% Pure Octene-1 5% Air-Blown Octene-1
4	2	70	5		95	95% Pure Octene-1 5% Air-Blown Octene-1

Referring to Table I, air-blowing the octene-1 for 2 hours at 70°C. resulted in only a 24 mole percent yield of primary alkyl bromide after a reaction time of 103 minutes. Example 2 shows that 6 hours of air-blowing at 70°C. was sufficient to result in a yield of primary alkyl bromide of over 90 percent in a reasonable reaction time of 6 minutes. In this application, "yield" means the conversion of the olefin times the efficiency of conversion of the olefin to the desired primary alkyl bromide. Examples 3 and 4 show that when air-blowing occurred in the presence of 5 percent of a previously air-blown activated octene-1, a time of 2 hours at 70°C. was sufficient to result in a yield of primary alkyl bromide of over 90 percent in a reaction time of 3 to 5 minutes. The 5 percent air-blown activated olefin

which was utilized in Examples 3 and 4 above was part of the product of Example 2 in Table I.

EXAMPLE 5

140 grams of a mixture of hexene-1 (95 weight percent) and activated octene-1 (5 weight percent) was air-blown for 2 hours at 60°C. The resulting mixture of olefins was found to give a yield of primary alkyl bromide of 96 mole percent in a hydrobromination reaction time of 5 minutes at -10° to 0°C.

EXAMPLE 6

140 grams of a mixture of 95 weight percent dodecene-1 and 5 weight percent of activated octene-1 was air-blown for 2 hours at a temperature of 70°C. Hydrobromination of this air-blown mixture of olefins for 5 minutes at -10° to 0°C. resulting in an 89 mole percent yield of primary alkyl bromides.

EXAMPLE 7

Example 6 was repeated except the 5 percent active octene-1 was not present. Only a 4-mole percent yield of primary alkyl bromide was obtained after a 30 minute reaction time.

A comparison of Examples 6 and 7 shows the importance of the presence of 5 weight percent of an active olefin in reducing the time required for activation.

In addition, it should be noted from Examples 5-8 that the activating olefin need not be the same olefin as the substantially pure olefin charge stock.

EXAMPLE 8

212.6 grams of octene-1 were air-blown at a temperature of 70°C. for 2 hours in the presence of 25 weight percent of previously blown activated octene-1. The resulting mixture of olefins was active for the hydrobromination reaction which is shown by the fact that more than a 90-mole percent yield of primary alkyl bromide was obtained at -12° to 0°C. in a time of less than 10 minutes.

A comparison of Example 8 with Example 6 shows that the presence of 25 weight percent activated olefin in the charge stock achieved about the same results as the presence of 5 weight percent activated olefin in the charge stock. Hence, while it is not detrimental to have larger amounts of activated olefin admixed with the substantially pure olefin, there is no advantage to this process to the presence of the larger quantities of activated olefin which merely serve to reduce the space time yield of products from the air-blowing reactor.

EXAMPLE 9

Example 6 was repeated except the amount of activated olefin in the charge stock to the air-blowing step was 2 weight percent. Six hours were required at 70°C. to activate the mixture.

A comparison of Examples 6, 7 and 9 shows that it required as much time with 2 weight percent activated olefin as with a 100 percent substantially pure olefin charge stock (Example 6).

A comparison of all of the above examples shows it is critical to employ an amount of activated olefin in the charge stock of at least about 4 weight percent to obtain the advantages of this invention, i.e., a reduction in

the minimum time required for activation of the olefin for hydrobromination.

The above data were obtained in a batch type reactor. In a continuous stirred tank reactor where inactive olefin is continuously added and active olefin is continuously removed, there is considerable backmixing which is equivalent to recycle of active olefin, and this type of recycle operation is, of course, meant to be included in this invention.

Resort may be had to such variations and modifications as fall within the spirit of the invention and the scope of the appended claims.

We claim:

1. A process for the preparation of a primary alkyl bromide from a substantially pure alpha-olefin having from four to 30 carbon atoms per molecule which comprises:

contacting at least one of said alpha-olefins in an air blowing zone with a gas containing free molecular oxygen at a temperature from about 60° to 200° C. for a time sufficient to result in activation of said olefin, said activated olefin being one which results in a yield of at least 85 mole percent primary alkyl bromide when reacted with anhydrous hydrogen bromide in the absence of an extraneously added catalyst at -10° to 0° C. in a reaction time of less than 15 minutes;

removing said activated olefin from said air-blowing zone; and

recycling a sufficient amount of said activated olefin 30

to equal at least 4 weight percent of the olefins entering said air-blowing zone; and thereafter reacting said activated alpha-olefin with anhydrous HBr in the absence of an extraneously added catalyst at a temperature less than 50° C. to produce the desired primary alkyl bromide.

2. A process according to claim 1 wherein said alphaolefin is one which has been intimately contacted with a Group IIIA metal alkyl having at least one carbon to metal bond.

3. A process according to claim 2 wherein the gas containing free molecular oxygen is air.

4. A process according to claim 3 wherein the alpha-olefin is octene-1.

5. A process according to claim 1 wherein said previously activated olefin has a different number of carbon atoms than said substantially pure alpha-olefin.

6. A process according to claim 5 wherein the substantially pure alpha-olefin is hexene-1.

7. A process according to claim 5 wherein the substantially pure alpha-olefin is dodecene-1.

8. A method according to claim 1 wherein said alpha-olefins contain from 4 to 50 weight percent of a previously activated olefin.

9. A method according to claim 8 wherein said alpha-olefin is obtained by the telomerization of ethylene under telomerization conditions in the presence of a Group IIIA metal alkyl.
